COMBINED FOOD MIXER AND BLENDER

Robert N. Freedman, Great Neck, N.Y., assignor to Vogue Electronic & Appliance Corp., a corporation of
New York

Filed Feb. 16, 1962, Ser. No. 68,858

Term of patent 14 years

(Cl. D89—1)

FIG. 1

FIGURE 1 is a perspective view of a combined food mixer and blender showing my new design;

I claim:

The ornamental design for a combined food mixer and blender, substantially as shown.
